CLAIM

The ornamental design for an earplug dispenser, as shown and described.

DESCRIPTION

FIG. 1 is a front perspective view of an earplug dispenser; FIG. 2 is a front elevation view thereof; FIG. 3 is a left side elevation view thereof, with the right side being a mirror image thereof; FIG. 4 is a back side elevation view thereof; FIG. 5 is a top plan view thereof; and, FIG. 6 is a bottom plan view thereof.
The broken lines depict portions of the article that form no part of the claimed design.
